UNITED STATES PATENT OFFICE.

JOHN T. CROWLEY, OF LAMBERTVILLE, NEW JERSEY.

RUBBER BOOT.

No. 864,616.

Specification of Letters Patent.

Patented Aug. 27, 1907.

Application filed January 7, 1907. Serial No. 351,202.

To all whom it may concern:

Be it known that I, JOHN T. CROWLEY, a citizen of the United States, residing at Lambertville, in the county of Hunterdon and State of New Jersey, have 5 invented new and useful Improvements in Rubber Boots, of which the following is a specification.

This invention relates to rubber boots, and the object thereof is to simplify the art of making boots of such class, as well as obtain a saving in material from which 10 the boot is made, and, furthermore, to provide a boot in which it is not necessary to employ the stiff tongues and double stock which a vamp and counter makes necessary in the rubber boots now in general vogue, and, consequently, by dispensing with such stiff 15 tongues and double stock the boot is made with such flexibility around the ankle so as to relieve the wearer from pressure at such point to enable the boot to be worn with comfort, and, furthermore, by such construction preventing the forming of sharp wrinkles in the 20 foot portion so that there will be no liability of the boot cracking or breaking.

In describing the method and article in detail reference is had to the accompanying drawings, in which—

Figure 1 is a perspective view of a rubber boot in 25 accordance with this invention. Fig. 2 is a view of the four quarters or sections of the boot.

A rubber boot in accordance with this invention comprises four longitudinal and unitary quarters or sections cut from suitable material and which are indicated by the reference characters 1, 2, 3 and 4, the 30 sections 1, 2 being similar in contour and the shape of the sections 3, 4 is the same. The sections 1, 2 are employed for the front half of the boot and the sections 3, 4 for the back half of the boot. Each of the sections 35 1, 2 is of a length substantially equal to the length of the front half of the boot and the length of the sections 3, 4 is substantially equal to the length of the back half of the boot, the sections 1, 2 being slightly greater in length than the sections 3, 4 so that when the 40 sections are secured together the top of the boot will be of a shape similar to the shape of the rubber boot now in general vogue. The section 1, as well as the section 2 at its bottom is so shaped as to form half of the upper portion and half of the front of the leg portion of the boot. The sections 1, 2 are adapted to overlap and the overlapping portions are connected together in a known manner and by such a step the front half of the boot is completed. The section 3, as well as the section 4, is so shaped as to form half of the heel portion 45 50 and half of the rear of the leg portion. The sections 3, 4 are adapted to overlap and the overlapping portions cemented together in a known manner and by such step the rear half of the boot is completed. The sections 1, 2 are then positioned to overlap, respectively, 55 the sections 3, 4 and the overlapping portions are cemented together in a known manner, thereby complet-

ing the boot above the sole and heel portions. The overlapping portions of the sections are indicated by the reference characters 1^a 2^a, and extend substantially the length of the boot.

60

The sole portion of the boot is indicated by the reference character 5 and is secured in a known manner to the bottom of the sections 1, 2, 3 and 4 after these latter are secured together in a manner as stated. To the sole portion 5 is secured in a known manner the heel 6. 65

In lieu of connecting the sections 1, 2 together and then connecting the sections 3, 4 together so as to form the front half and rear half of the boot, after which the said front and rear halves are cemented together the front section 1 may be secured to the rear section 3 and 70 the front section 2 to the rear section 4, after which the front sections can be secured together, as well as the rear sections. The sections 1, 2, 3 and 4 are so shaped as to impart when connected together the necessary form for the foot and leg portions of the boot.

75

Cemented to the outer face of the sections 1, 2, 3 and 4 and extending from the sole portion to and upon the leg portion are the stays 7, 8 at the front of the boot and the stays 9 at the heel of the boot and the said stays are employed so as to dispense with the tongues of the 80 vamps and counters used in the style of rubber boot now in vogue.

It will be evident that in forming a rubber boot in a manner as stated the material from which the boot is to be formed can be cut in an unusually economical manner, consequently, saving material, and, furthermore, the art of making the boot is extremely simplified. Then again, dispensing with the tongues of the vamps and counters the boot at the ankle portion is unusually 85 flexible so that the boot can be conveniently worn, and, owing to said flexibility wrinkles are prevented when wearing the boot and by preventing wrinkles there is 90 no liability of the boot cracking or breaking.

What I claim is—

1. As a new article of manufacture a rubber boot having its foot and leg portions formed of four unitary sections overlapping each other and secured together, each of said sections of a length substantially equal to the length of the boot, and stays secured to the periphery of the front and heel portions of the boot.

95

2. As a new article of manufacture, a rubber boot comprising a pair of longitudinal sections constituting the rear of the boot and a pair of longitudinal sections constituting the front of the boot, each of the rear sections being of the same contour and each of the front sections being of the same contour, the contour of the front sections differing from the contour of the rear sections, each of said sections of a length substantially equal to the length of the boot, said sections having their longitudinal edges overlapping and secured together, each of said front and rear sections comprising a part of a leg and a part of a foot portion, and stays secured to the periphery of the front and heel portions of the boot.

100

3. As a new article of manufacture, a rubber boot comprising a pair of longitudinal sections each of a length 110 equal to the length of a boot at the rear thereof and con-

115

stituting the rear half of a boot, said sections at their rear overlapping each other in the direction of their length and secured together, a pair of longitudinal sections each of a length equal to the length of the boot at 5 the front thereof and overlapping each other at the front in the direction of the length thereof and with the overlapping portions secured together, each of the rear sections being of the same contour and each of the front sections being of the same contour, the contour of the 10 front sections being different from the contour of the rear

sections, each of said front and rear sections comprising part of a leg and part of a foot portion, said front sections being secured at their rear to the front of the rear sections.

In testimony whereof I have hereunto set my hand in 15 presence of two subscribing witnesses.

JOHN T. CROWLEY.
